UNITED STATES PATENT OFFICE.

PAUL OLUFF POULSON, OF BRIGHAM, UTAH.

EXPLOSION-TURBINE.

No. 914,072.

Specification of Letters Patent.

Patented March 2, 1909.

Application filed April 15, 1908. Serial No. 427,239.

To all whom it may concern:

Be it known that I, PAUL O. POULSON, a citizen of the United States, and a resident of Brigham, in the county of Boxelder and State of Utah, have invented a new and Improved Explosion-Turbine, of which the following is a full, clear, and exact description.

This invention relates to turbines and gas engines, and the object of the invention is to produce a turbine which will be propelled by exploding charges within the same. The general purpose is to produce a prime mover of this class which will be efficient in operation and extremely simple in construction.

The invention consists in the construction and combination of parts to be more fully described hereinafter and particularly set forth in the claims.

Reference is to be had to the accompanying drawings forming a part of this specification, in which similar characters of reference indicate corresponding parts in all the views.

Figure 1 is a longitudinal vertical section taken through an explosion turbine constructed according to my invention; Fig. 2 is a vertical cross section taken through the engine on the line 2—2 of Fig. 1; and Fig. 3 is an end elevation of the engine showing the upper portion thereof as viewed from the left of Fig. 1.

Referring more particularly to the parts, 1 represents the main frame of the engine, and 2, 2 represent pedestal bearings for the 35 shaft 3 of the engine. To the end of this shaft there is attached a rotor or wheel 4 which has an enlarged hub 5 connected by a disk body 6 with a rim 7. On the inner side of this rim 7 a plurality of buckets 8 are 40 formed as indicated most clearly in Fig. 2. These buckets are slightly curved rearwardly with respect to the direction in which the rotor rotates. At the rim 7 an inwardly 45 projecting flange 9 is formed on the side thereof opposite to the disk body 6, and this flange is provided with a plurality of exhaust openings 10 disposed respectively between the buckets 8 as indicated. In the disk body 6 I provide a plurality of openings 50 11 which communicate with the atmosphere, and these openings are covered by hoods 12 which are adapted to catch the air and draw the same into the body of the rotor as it rotates.

Within the rotor 4 there is provided a rigid stator 13, the construction of which is

clearly shown in Fig. 2; it has the outline of a drum having a slightly smaller diameter than the internal diameter of the rotor, from which arrangement the inner edges of 60 the buckets 8 lie close to the face of the stator, as indicated in Fig. 2. Although this stator presents the outline of a drum, its body is cut away as indicated in Fig. 2, so as to form an explosion chamber 14. The side 65 walls of this explosion chamber are curved as indicated at 15 and 16, so as to act as guides tending to direct the gases of combustion in the direction in which the rotor rotates. In this way two oppositely disposed abutments 17 are formed having enlarged ends 18 and reduced or tapered ends 19. Between the enlarged end of one abutment and the small end of the opposite abutment, guide vanes 20 are provided, which 70 are curved, as shown, in the direction in which the rotor rotates. These abutments 17 and guide vanes 20 extend continuously 75 across the rotor, connecting the side plates 21 thereof, as shown. This stator is rigidly 80 supported upon brackets 22, which are supported upon a frame plate 23 which surrounds the main frame 1, as shown in Fig. 3.

On the interior of the rotor and on the side face thereof which is disposed adjacent 85 to the main frame 1, an igniting pan or plate 24 is attached. This plate has a shallow dished body, as indicated in Fig. 2, the outer end whereof is turned vertically to form a wing 25. The outer side wall of the stator 90 opposite to this wing 25 is provided with an injector opening 26, and this opening is in alignment with a duct 27 which is formed in the end of a feed chest 28. This feed chest has a horizontal barrel or cylinder 29 formed 95 therein, in which a plunger or piston 30 reciprocates. The forward part of the barrel or cylinder 29 is provided with an upwardly extending port 31 which communicates with a valve chest 32 in which valve chest there 100 is guided a slide valve 33 having a vertically disposed feed opening 34 therethrough, as shown. Above the valve chest 32 an inlet connection 35 is provided through which gasolene is drawn in. This inlet connection 105 35 communicates with a bonnet 36 having a vertical bore in which a governor plunger 37 operates. On the bonnet 36 there is seated a governor 38, the stem 39 of which is adapted to be raised and lowered in the usual manner by means of governor weights 40 which fly outwardly as the speed of the engine in-

creases. In this way the stem 39 may move the plunger 37 downwardly so as to partially or completely obstruct the inlet opening 35. In this way the engine governs itself automatically. Near the igniting pan 24 a spark plug 41 is provided. The plunger 30 and the parts co-operating therewith constitute an injector for forcing the charges of gasoline into the interior of the stator.

10 In order to operate the valve 33 and the plunger 30 automatically, the hub 5 is provided with a cam groove 42. This cam groove operates a lever 43 mounted upon a bracket at 44, and the lower end of this lever 15 operates a slide rod 45 which passes longitudinally of the engine near the base plate 46 thereof. The end of this slide rod 45 is attached to an arm 47 of a segment 48, and this segment meshes with a segment 49 20 which is rigid with a plunger arm 50. This plunger arm 50 is connected by a link 51 with a plunger rod 52 which is attached to the plunger 30. The end of the slide rod 45 is also connected with a valve lever 53 which 25 is pivotally mounted on the frame as indicated at 54. The connection between the rod 45 and the lever 53 may be by pin and slot if found desirable in practice. The upper end of this lever 53 has a pin-and-slot 30 connection with the valve stem 55, which projects from the valve as indicated.

In the stator just below the ignition pan 24 there is provided an air valve 56 which opens inwardly so as to admit atmospheric air at the proper time into the interior of the stator. It is mechanically operated by a link 56^a from the lever 53.

The governor 38 is driven by a horizontal governor shaft 57 running parallel with the 40 main shaft 3, and driven therefrom by a suitable belt 58, as shown. The shaft 3 is provided with a suitable belt pulley 59 for driving machinery from the engine.

The outer face of the flange 9 is substantially covered by exhaust rings 60, but the upper and lower ends of these rings are separated so as to form gaps, as indicated at 61 and 62, and when the exhaust ports 10 are passing these gaps exhaust takes place.

50 In order to center the rotor accurately on the stator, the end of the shaft 3 is formed with a tapered projecting nose 63 which extends into the interior of the rotor, and the adjacent face of the rotor is formed with a 55 small counterbore 64, which receives this nose and centers the stator, as will be readily understood.

The mode of operation of the engine will now be described: As the rotor rotates, the 60 cam groove 42 rocks the cam lever 43 and reciprocates the slide rod 45. In this way the valve 33 and the plunger 30 will be reciprocated in opposite directions; the travel of the valve 33 is sufficient to bring the port 34 65 thereof under the bonnet 36, so that a charge

of gasoline descends into the valve. When the valve is at the limit of its forward movement, as indicated in Fig. 1, this charge may pass down the port 31 into the forward end of the barrel or bore 29. Then, with the forward movement of the plunger 30 this charge is injected through the duct 27 into the interior of the stator, striking against the wing 25 so as to be transformed into a spray. It will be noted that the wing 25 is disposed substantially at right angles to the path of the charge of fuel as it is projected violently into the explosion chamber by the injector. The high temperature within the explosion chamber of the stator and the air which is supplied through the valve 56, forms an explosive mixture which is ignited by the electric spark produced at the sparking plug 41. When the explosion takes place the gases of combustion which are at a high pressure, 75 tend to find exit from the explosion chamber. In flowing out, they are directed by the faces 15 and 16 and the vanes 20, in the direction in which the rim of the rotor moves. In this way they exert their energy upon the inner 80 faces of the buckets 8 and rotate the rotor. As the buckets 8 pass the open exhaust ports at the upper and lower side of the engine, exhaust takes place. If the engine should tend to run too fast, the governor will move the 85 plunger 37 downwardly so as to choke the supply of fuel.

While I have intended this turbine to be used especially as an explosion turbine, the rotor and stator may be used as a steam turbine by admitting steam to the interior of the stator at the point where the injector is located. The interior of the stator will then constitute a steam space from which the steam flows outwardly against the buckets 8 100 in such a way as to cause the rotor to rotate.

Having thus described my invention, I claim as new and desire to secure by Letters Patent:

1. In an explosion turbine, in combination, a stator having an explosion chamber therein, a rotor surrounding said stator, having buckets receiving the gases of combustion from said stator, an injector for projecting charges of liquid fuel into said explosion chamber, a pan within said explosion chamber and having a part projecting substantially at right angles across the path of the incoming charge, means for admitting air to said explosion chamber, and means for igniting the explosive mixture formed therein. 110

2. In an explosion turbine, in combination, a stator having the form of a drum, an explosion chamber in the interior thereof, said drum having openings in the side wall 125 thereof, a rotor having a disk body seating against the side of said drum and having a rim projecting over the side wall thereof, said rim having a flange at the edge thereof 120 projecting toward said stator and lying 130

substantially against the side face thereof, said flange having exhaust openings therethrough, said rim having buckets formed on the inner face thereof receiving the propelling gases from the openings in said stator, said exhaust openings being disposed adjacent to the lateral side edges of said buckets, means for feeding explosive charges into said explosion chamber, and means for igniting said charges.

3. In an explosion turbine, in combination, a stator of substantially cylindrical form, having an explosion chamber formed therein and having openings in the side wall thereof, a rotor having a disk body seating against the side of said stator having a rim projecting across the face of said stator, said rim having a flange projecting toward said stator and having exhaust openings therethrough adjacent the side edges of said buckets, said rim having buckets formed on the inner faces thereof, means for feeding explosive charges into said explosion chamber, means for igniting said charges, said rotor having openings in the disk body thereof on the side of said stator exposing portions of said disk body and communicating with the atmosphere to cool said stator.

4. In an explosion turbine, in combination, a stator having an explosion chamber therein, a rotor receiving the gases of combustion from said explosion chamber, a feed chest having a barrel therein, a plunger reciprocating in said barrel, said feed chest having a duct leading from said barrel into said explosion chamber, a valve chest having a port communicating with said barrel, a valve reciprocating in said valve chest and

having a chamber therein, means for admitting a liquid fuel to said valve chamber, said valve chamber being adapted to communicate with said port to pass said liquid fuel into said barrel, an igniting device within said explosion chamber, and means for admitting air to said explosion chamber.

5. In an explosion turbine, in combination, a stator having an explosion chamber therein, a rotor receiving the gases of combustion from said explosion chamber, a feed chest having a barrel formed with a duct communicating with said explosion chamber, an ignition pan within said stator opposite said duct, a valve adapted to admit charges of liquid fuel to said barrel, a plunger reciprocating in said barrel, said rotor having a hub with a cam groove formed therein, and means for actuating said valve and said plunger from said cam groove.

6. In a turbine, in combination, a rotor having a flange with exhaust openings therein, and buckets projecting inwardly from said flange, a stator adapted to receive an operating fluid and affording means for directing the said operating fluid against said buckets in the direction of rotation of said rotor, and an exhaust ring disposed over said flange and having openings at which said first openings become uncovered to permit exhaust.

In testimony whereof I have signed my name to this specification in the presence of two subscribing witnesses.
